(57) **CLAIM**

The ornamental design for a condensing unit air discharge combined grille and panel, as shown and described.

DESCRIPTION

FIG. 1 is a front view of a condensing unit air discharge combined grille and panel.

FIG. 2 is a side view of the grille of FIG. 1.

FIG. 3 is a top view of the grille of FIG. 1; and,

FIG. 4 is a perspective view of the grille of FIG. 1 installed on a condensing unit.

A bottom view and second side view are omitted as being duplicative of the views above and a rear view is further omitted as containing no additional surface ornamentation.

The broken line showing of a condensing unit air discharge grille is included for the purpose of illustrating environmental structure and forms no part of the claimed design.
